United States Patent Office

Des. 228,958
Patented Oct. 30, 1973

228,958

VARIABLE AMOUNT IMPRINTER

Franklin O. Geiger, Manassas, Va., assignor to Farrington
Business Machines Corporation, Springfield, Va.

Filed Aug. 1, 1972, Ser. No. 277,081

Term of patent 7 years

Int. Cl. D18—02

U.S. Cl. D64—11 B

FIG. 1

FIG. 2

FIG. 3

FIG. 1 is a front perspective view of a variable amount imprinter showing my new design;

FIG. 2 is a top plan view; and

FIG. 3 is a front elevational view thereof with parts broken away and in section to better illustrate the sunken keyboard.

I claim:

The ornamental design for a variable amount imprinter, as shown.
